(57) **CLAIM**

The ornamental design for a garment with pocket, as shown and described.

DESCRIPTION

FIG. 1 is a front perspective view of one embodiment of a garment with pocket showing my new design;

FIG. 2 is a front view thereof with a portion of the garment with pocket removed for clarity of disclosure to expose the pocket. The pocket is located on the inside surface of the rear of the garment. The wavy broken line shown represents the boundary of the front of the shirt shown cut away;

FIG. 3 is a rear view thereof;

FIG. 4 is a cross-section taken along line 4-4 of FIG. 2, showing the pocket in a closed condition; and,

FIG. 5 is a cross-section taken along line 5-5 of FIG. 2, showing the pocket in an opened condition.

The dot-dash broken lines showing sleeves, a placket and collar represent portions of the garment with pocket which form no part of the claimed design. The dashed broken lines near the bottom of the garment with pocket represent stitching and also form no part of the claimed design. The wavy broken lines shown in FIG. 2 represent the boundary of the portion of the front of the garment with pocket removed for clarity of disclosure, and also form no part of the claimed design.
